UNITED STATES PATENT OFFICE.

ORSINI STUART, OF LIVERPOOL, ENGLAND.

CLOSURE-FASTENER.

1,382,567.

Specification of Letters Patent. Patented June 21, 1921.

Application filed October 16, 1919. Serial No. 331,097.

To all whom it may concern:

Be it known that I, ORSINI STUART, subject of the King of Great Britain, residing at Liverpool, in the county of Lancaster and 5 Kingdom of England, have invented certain new and useful Improvements in Closure-Fasteners, of which the following is a specification.

This invention is an improvement in or 10 modification of the invention set forth in Specification No. 119501 and has reference to doors applicable for smoke boxes, and for closing the openings or ways through bulkheads, partitions, walls and the like, where 15 it is desired to make a practically fluid tight or fireproof door which can be readily opened and closed.

These improvements relate to the means 20 by which a water, steam or gas tight joint is obtained when the door is closed, also to certain constructional features of the door fastening means. They also relate to mechanism by which the door fastening means is only allowed to be slid into the shot 25 position when the door is completely closed.

These improvements will be understood 30 from the following description reference being had to the accompanying drawings in which:—

Fig. 1 is a front elevation of the door; 35 Fig. 2 is a longitudinal cross section on the line A B of Fig. 1;

Fig. 3 is a horizontal cross section on the line C D of Fig. 1; and

Fig. 4 is a detail view of one of the fastening devices.

Fig. 5 is a fragmentary front elevation on an enlarged scale of the interlock mechanism for holding the locking bar in retracted 40 position.

Fig. 6 is a section on the line 6—6 of Fig. 5 showing the position assumed by the parts in open and partly opened positions of the door.

Fig. 7 is a view similar to Fig. 6 showing the position assumed by the parts in the closed position of the door.

Referring first to Figs. 1 to 4 of the drawings, 1 represents a portion of a partition, 50 or bulkhead in which there is an opening or doorway having a flange or rib 1^x all around its edge against which rests (in its closed position) the packing carried by the door plate 2, the said door plate being hinged by hinges such as 3 to the partition 1. The

door plate 2 is off-set outwardly all around the edge 2^x to strengthen the door and also to form a recess in which is inserted a packing or jointing 4 of india rubber or other suitable material, this jointing material being held in position in the said recess by clamping strips 5 but in such manner as to leave a part 7 of the said jointing material, which is coincident with the ribs 1^x exposed, so that such part 7 will contact firmly with the said rib 1^x when the door is closed and 60 form a water, steam and gas tight joint. The door plate has a marginal frame 8 (made of metal angular in cross section) applied to it, that is to say, one edge is made 65 with a projecting rib 8^x, and this marginal frame, which embodies three sides of a rectangle, has a sliding movement in suitable guide pieces 9 riveted to the door plate, the ends of such guide pieces being arranged to 70 overlap the marginal frame so that the latter cannot be separated from the door plate. The said marginal frame rests against the off-set portion 2^x of the door plate, and riveted to it are the wedge bars 10 and 11. 75 These take into beveled flanges or sockets 12 and 13 which are riveted to the partition 1 adjacent to the doorway or opening therein. The flanges or sockets 12 are beveled as shown in Fig. 3, and the flanges or sockets 13 80 are beveled as shown in Fig. 4 so that when the door is closed, the sliding of the marginal frame will cause the wedge bars 10 and 11 to wedge themselves into their respective flanges or sockets 12 and 13 thus 85 pressing the jointing material 4 at all the four sides of the perimeter of the door plate against the rib 1^x of the doorway opening and make a water, steam or gas tight joint. 90 The member of the marginal frame opposite to that of the hinges 3, lies coincident with the off-set portion 2^x only when the door is in the fastened position, while the other two members of the marginal frame always lie coincident with the said off-set portion, 95 whether the door is in the fastened position or not.

The fastening of the door and the wedging action to make a water, steam or gas tight joint, is effected by sliding the marginal frame in one direction, and the release of the wedging action and unfastening of the door is effected by sliding the marginal frame in the other direction. This sliding 100 movement is imparted to the marginal 110

frame by means of a cam 14 secured to the spindle 15 journaled in the door plate 2, the said cam being confined between the marginal frame 8 and an abutment 16 secured 5 by arms 17 to the said frame 8. By turning one or other of the handles 18, the cam will impart to the said frame 8 a sliding movement in one direction to fasten the door, or in the other direction to unfasten it.

10 The hinges 3 are so arranged relatively to the door and stationary partition 1, that in the act of closing the door, the jointing material at the side of the door plate adjacent to the hinges will first impact against 15 the complementary rib 1^x of the doorway opening and the complete closing of the door will exert a leverage which binds the said jointing material against the said rib as to produce a very secure water tight 20 joint. If desired the hole in the hinges 3 through which the pins pass may be made oval to permit of the door closing toward the partition 1 after the said jointing material at the side adjacent to the hinges has 25 impacted against the complementary rib 1^x. At the other three sides of the perimeter of the door plate 2 a very secure joint is produced by the action of the wedge bars 10 and 11 which take into the beveled flanges 30 or sockets 12 and 13, so as to bind the jointing material at top and bottom of the door and at the side of the door opposite to the hinges, against its complementary ribs 1^x. Consequently the ribs bear equally at all 35 points on the jointing material and insure a perfect joint.

It will be readily understood that it is most important there should be no obstruction to prevent the door being closed quickly 40 and promptly, when any emergency arises. If by accident or otherwise, the marginal frame with its wedge bars were slid into the shot or partly shot position before the closing of the door had been effected an obstruction to the doors closing would be 45 caused, which would result in delay, and this in the confusion that sometimes happens when an emergency occurs, might be fatal. In order to prevent this I provide a mechanism 50 by which the wedge bars are held locked in the withdrawn position so that they cannot be shot outward until the door is completely closed. This mechanism shown in Figs. 5 to 7, as applied to the door of 55 Figs. 1 to 4, consists of a locking device which only becomes operative when the door is open or partly open, that is to say it becomes operative immediately the handle is turned to unlock the door and which continues in operation until the door is closed 60 again. This locking device may be arranged to interlock with a part in connection with the handle, or to interlock with the wedge bars or with the marginal frame, so that 65 the handle cannot be turned until the door

is again closed. I show in the drawings the latter arrangement, but recognize that the specific form and location of the device are subject to modification.

This device is best shown in Figs. 5, 6 70 and 7. The arm or tappet marked 43 is pivoted in a bracket 44 secured to the door plate 2, such arm or tappet being shaped at its outer end so as to impact against the partition or bulkhead 1 or other suitable abutment when the door is closed, while the inner end of this arm or tappet has a spring 45 in connection with it, so arranged as to keep the outer end of the tappet projecting beyond the inner face of the door when the 75 door is open. This arm or tappet projects across the marginal frame 8, which has a transverse notch 46 in it adjacent to the said tappet 43 and the spring 45 (when the door is open) keeps the tappet in locking 80 engagement with the notch 46. Therefore so long as the door is open or partly open the tappet 43 engaging this notch 46, prevents the marginal frame with its wedge 85 pieces being moved, but when the door is closed the outer end of the tappet impacting against the partition or bulkhead 1 turns the tappet on its pivot 47, thus lifting it out of engagement with the notch 46 and enabling the operating handle 18 to be 90 turned. Instead of a notch, a shoulder or other device could be arranged on the tappet to engage with the marginal frame or a 95 wedge bar.

I declare that what I claim is:—

1. The combination of a door frame, a door hinged thereto, a shiftable locking frame and coacting keeper, one mounted on the door frame and the other on the door; a releasable interlock device operatively related to said locking frame to retain the same in disengaged position; and means operated by the movement of the door near the limit of its closing movement serving to release said interlock and permit movement of 105 said frame.

2. The combination of a door frame; a door hinged thereto; a shiftable locking frame and coacting keeper one mounted on the door frame and the other on the door; a yielding latch serving when projected to hold the locking frame against movement; and a member operable by the relative movement of the door and frame as the door nears its closed position, and serving when operated to retract said latch.

3. The combination of a door frame; a door hinged thereto; a locking frame movably mounted in said door and having a plurality of beveled locking lugs; keepers mounted in said door frame and adapted to receive said beveled lugs; a spring-urged latch mounted on said door in position to be engaged and held retracted by said door frame when the door is closed, and a stop in 125 130

said locking frame adapted to be engaged by said latch when the latter is projected to preclude movement of said locking frame.

4. The combination of a door frame provided with a rib projecting from its face and surrounding the door opening, a door plate hinged to said frame and formed with a recess opposed to said rib when the door is closed; jointing material clamped in said recess and serving to seal against said rib when the door is closed; a marginal frame slidably mounted on the face of the door plate; wedge lugs secured to said marginal frame and projecting beyond the edge of said door

plate; keepers mounted on the door frame 15 having beveled recesses serving to receive the said lugs when the frame is slid in one direction and to release said lugs when it is slid in the opposite direction; and means for shifting said frame in opposite directions. 20

In witness whereof I have hereunto signed my name this 2nd day of Oct. 1919, in the presence of two subscribing witnesses.

ORSINI STUART.
